CARTON

Patrick A. Toensmeier, Catonsville, Md., assignor
to The Bartgis Brothers Company, Ilchester,
Md., a corporation of Maryland

Application November 13, 1950, Serial No. 195,155

5 Claims. (Cl. 229—15)

1

This invention relates to cartons for use in the distribution of various articles and is concerned more particularly with a novel carton, which is provided with a handle, so that it may be easily carried. The new carrier carton is of simple construction and it includes side and end walls of uniform height, on which printed matter may be placed. Initially, the handle is wholly within the outlines of the carrier, so that a plurality of the loaded carriers may be stacked one upon another to provide a display. When the handle of the carrier is grasped and pulled, the handle rises, until its upper end lies above the top of the walls in position to be easily gripped. The new carrier may be used to especial advantage in the packaging of such articles as a number of cans of beer to be sold as a unit, and a form of the carrier for that use will be illustrated and described for purposes of explanation.

At the present time, it is the practice of breweries selling beer in cans to supply their retailers with cartons containing a plurality of cans. These cartons are of ordinary construction and are not provided with handles. They can, accordingly, be stacked one upon another for shipment and display, but they are bulky and awkward to handle. Carriers with handles, such as are used in the distribution of bottled beverages, are easy to handle but they cannot ordinarily be stacked, and thus occupy much space in shipment and in the retail store.

The present invention is directed to the provision of a carrier carton which overcomes the disadvantages, while retaining the advantages, of both the beer cartons and bottle carriers referred to above. The new carrier is made of paperboard stock and it includes side and end walls, a bottom, and a longitudinal partition including two plies separated over a central area to receive a handle between them. The handle is made of paperboard, preferably of two plies, and initially it is detachably connected to the partition and lies wholly below the top of the walls with its upper end exposed in a cut-out in the partition. When the handle is grasped and pulled, it is easily detached at its original connection to the partition and rises to engage the partition at a higher level. The upper end of the handle, which is provided with finger openings, then projects above the top of the carrier, where the handle can be easily gripped. Whenever the carrier is put down and the handle released, the handle drops or can be pushed down to its initial position, so that the carrier can be again stacked.

2

For a better understanding of the invention, reference may be made to the accompanying drawings in which:

Fig. 1 is a view in perspective of the new carrier with parts broken away;

Fig. 2 is a view in perspective of the carrier with the handle raised;

Fig. 3 is a transverse vertical section through the carrier with the handle raised and on the line 3—3 of Fig. 4;

Fig. 4 is a vertical longitudinal sectional view on the line 4—4 of Fig. 3;

Fig. 5 is a plan view of the collapsed carrier;

Fig. 6 is a sectional view on the line 6—6 of Fig. 5;

Fig. 7 is a plan view of the blank from which the carrier is made;

Fig. 8 is a plan view of the carrier blank at an intermediate stage in the completion of the carrier; and

Fig. 9 is a plan view of the carrier blank just before the final stage in the completion of the carrier.

The carrier in the form shown is of a size for receiving six cans, arranged in two rows of three each, and it is made from the blank shown in Fig. 7. The blank comprises a pair of like side walls 10, 11, separated by a cut 12, and the side wall 10 has like end walls 13, 14 attached thereto along creased lines 15, 16, respectively. Similarly, side wall 11 is attached to end walls 17, 18 along creased walls 19, 20, respectively. End wall 14 is connected to a partition member 21 along a creased line 22, and end wall 18 is similarly connected to a partition member 23 along a creased line 24. The partition members are alike and they are connected together along a creased line 25. A cut-out 26 is formed in the adjacent edges of members 21, 23.

End wall 13 is connected to one part 27 of a handle member along a creased line 28, and end wall 17 is similarly connected to a second handle member 29 along a creased line 30. The handle members are connected along a creased line 31 and part 32 of a handle is connected to handle member 27 along a line 34, in which the stock is nearly completely severed. Part 33 of the handle is similarly connected to handle member 29 along a line 35. Each handle part is formed with a pair of shoulders 36 and an extension 37 between the shoulders, the extension being provided with finger openings containing flaps 38, severed on three sides. The ends of the extensions 37 of parts 32, 33 are connected along a creased line 39. A bottom wall 40 is connected to side wall

11 along a creased line 41 and is subdivided by a transverse creased line 42. At the free end of the bottom wall, it is provided with a glue flap 43, connected to the bottom wall along a creased line 44.

In forming the carrier from the blank described, the blank is laid flat and glue is applied to the upper faces of the handle members 27, 29, as indicated by the stippled area in Fig. 7. The partition made of members 21, 23 is then folded inwardly on creased lines 22, 24 to overlie end walls 14, 18 and portions of side walls 10, 11. The assembly, comprising end walls 13, 17, the handle members 27, 29, and the handle parts 32, 33, is then folded inwardly on lines 15, 19, so that the glued areas on the handle members overlie the upper face of the partition and secure the parts together. This condition of the blank is illustrated in Fig. 8, in which it will be seen that the extensions 37 on the handle members lie in alignment with the cut-out 26 in the partition. When the parts have been folded as described, a portion of the partition adjacent lines 22, 24 is exposed beyond the edge of the handle members and handle parts. Glue is now applied, as indicated by the stippled areas in Fig. 8, over the upper surface of handle member 29, handle part 33, and the exposed surface of ply 23 of the partition. The blank is then folded on lines 25, 31, and 39 and this results in the handle members 27, 29 being secured face to face and the two parts 32, 33 of the handle being secured face to face. Glue is now applied to the upper surface of glue flap 43 and the bottom wall is folded on its central creased line 42 to cause the glue flap to overlie the upper face of side wall 10 as shown in Fig. 5. The carrier is now complete and in collapsed condition, and portions of the handle parts 32, 33, adjacent the creased line 39 are exposed through cut-out 26.

When the carrier is to be erected, pressure is applied to the ends formed by creased lines 15, 19 and 22, 24. As a result, the end walls 13 and 17, which have been lying face to face, swing into edgewise alignment, and end walls 14, 18 are similarly moved into the same plane. Also, the two parts of the bottom, which have been lying face to face, move into the same plane. The carton is now in the condition shown in Fig. 1 and ready for loading. At this stage, the top of the two-part handle, defined by creased line 39 lies flush with the top of the partition, defined by creased lines 25. The handle members lie face to face between the plies of the partition and are secured to the plies thereof. The parts 32, 33 of the handle are secured face to face and are held by their weak connections 34, 35 to the handle members below cut-out 26. When the carton is to be picked up, a light pull on the part of the handle exposed through cut-out 26 breaks the connections 34, 35 and the handle may then be raised until its shoulders 36 engage the top of the partition beneath the folded lines 25. In this position of the handle (Fig. 2), the flaps 38 within the finger openings in the handle may be pushed through the openings and folded upwardly against the side of the handle, so that the handle may be readily grasped and the fingers protected by the lines of folding of the flaps. When the carrier is set down and the handle released, the handle may be pushed back to its original position, as shown in Fig. 1, so that the filled carriers can be stacked one upon the other, without interference from the handle.

I claim:

1. A carrier, which comprises a pair of like

side walls, an end wall attached to each side wall at each end thereof, a bottom wall connected to the side walls at their lower ends, a partition extending lengthwise within the carrier and connected to the end walls at opposite ends thereof, the partition including a pair of plies and a handle member lying between and secured to the inner faces of the plies below the lower edge of a central area of the plies extending downward from the upper ends of the plies, the plies having registering cut-outs extending downward from the upper ends thereof and lying within said area, the plies also having portions of their upper edges connected together at opposite sides of the cut-outs, and a handle detachably secured to the handle member lying between and free of said plies of the partition within said central area thereof, the handle having a neck of less width than the registering cut-outs and in line therewith and ears at its sides lying beneath the connected upper edges of the plies and engageable therewith upon detachment and raising of the handle.

2. A carrier, which comprises a pair of like side walls, an end wall attached to each side wall at each end thereof, a bottom wall connected to the side walls at their lower ends, a partition extending lengthwise within the carrier and including a pair of plies connected to respective end walls at one end of the carrier and a handle member connected to at least one end wall at the other end of the carrier and lying between and secured to the inner faces of the plies below the lower edge of a central area of the plies extending downward from the upper ends of the plies, the plies having registering cut-outs extending downward from the upper ends thereof and lying within said area, the plies also having portions of their upper edges connected together at opposite sides of the cut-outs, and a handle detachably secured to the handle member and lying between and free of the plies of the partition within said central area thereof, the handle having a neck of less width than the registering cut-outs and in line therewith and ears at its sides lying beneath the connected upper edges of the plies and engageable therewith upon detachment and raising of the handle.

3. A carrier, which comprises a pair of like side walls, an end wall attached to each side wall at each end thereof, a bottom wall connected to the side walls at their lower ends, and a partition extending lengthwise within the carrier and including a pair of outer plies connected to respective end walls at one end of the carrier and a handle member made of two plies connected to respective end walls at the other end of the carrier, said outer plies having registering cut-outs extending downward from the upper edges of said plies and portions of said upper edges connected together at opposite sides of the cut-outs, the plies of the handle member being connected together face to face and secured to the inner faces of the outer plies below the lower edge of a central area of said outer plies extending downward from the upper edges of said outer plies and including the cut-outs, the upper portion of the handle member lying within said area and being free of said outer plies and formed as a handle detachably secured to the remainder of the handle member, said handle having a neck of less width than the registering cut-outs and in line therewith and ears at its sides lying beneath the connected upper edges of said outer plies and engageable therewith upon detachment

of the handle from the remainder of the handle member and raising of the handle.

4. A carrier, which comprises a pair of like side walls, an end wall attached to each side wall at each end thereof, a bottom wall connected to the side walls at their lower ends, a partition extending lengthwise within the carrier and connected to the end walls at opposite ends thereof, the partition including a pair of plies and a handle member lying between said plies and secured to the inner faces thereof below the lower edge and along one side of a central area of the plies extending downward from the upper edges of the plies, the plies having registering cut-outs extending downward from the upper edges of the plies and lying within said area, the plies having portions of their upper edges connected together at opposite sides of the cut-outs, and a handle detachably secured to the upper edge of the handle member and being free of said plies and lying between said plies within said central area thereof, the handle having a neck of less width than the registering cut-outs and in line therewith and ears at its sides lying beneath the connected upper edges of the plies and engageable therewith upon detachment of the handle from the handle member and raising of the handle.

5. A carrier, which comprises a pair of like side walls, an end wall attached to each side wall at each end thereof, a bottom wall connected to the side walls at their lower ends, a partition extending lengthwise within the carrier and including a pair of plies connected to respective

end walls at one end of the carrier and extending substantially to the other end of the carrier and a handle member connected to the end walls at said other end of the carrier and lying between and secured to the inner faces of the plies below the lower edge and along one side of a central area of the plies extending downward from the upper edges of the plies, the plies having registering cut-outs extending downward from the upper edges of the plies and lying within said area, the plies also having portions of their upper edges connected together at opposite sides of the cut-outs, and a handle detachably secured to the handle member and lying between the plies of the partition within said central area thereof and free of said plies, the handle having a neck of less width than the registering cut-outs and in line therewith and ears at its sides lying beneath the connected upper edges and engageable therewith upon detachment of the handle from the handle member and raising of the handle.
